UNITED STATES PATENT OFFICE

139,813

DESIGN FOR A PIN OR SIMILAR ARTICLE OF JEWELRY

Joseph Walker, Canonsburg, Pa.

Application June 19, 1944, Serial No. 114,103

Term of patent 14 years

(Cl. D45—19)

To all whom it may concern:

Be it known that I, Joseph Walker, a citizen of the United States of America, residing at Canonsburg, county of Washington, and State of Pennsylvania, have invented a new, original, and ornamental Design for a Pin or Similar Article of Jewelry, of which the following is a specification, reference being had to the accompanying drawing, forming a part thereof, wherein:

I claim:

The ornamental design for a pin or similar article of jewelry, as shown.

JOSEPH WALKER.
